AIR CONDITIONING CONTROL
CIRCUIT

John S. Baker, Chicago, Ill., assignor to Cook
Electric Company, Chicago, Ill., a corporation
of Illinois

Application September 20, 1933, Serial No. 690,216

14 Claims. (CL 236—44)

This invention relates to improvements in air-conditioning systems, and, more particularly, to forced air circulating systems equipped with washers or with washers and filters.

Heretofore, it has been customary in such installations to provide a washer consisting of suitable spray heads which are fed from a suitable water pipe line. In this line is generally placed a magnetic valve controlled by a humidistat which is so arranged that when the air is sufficiently dry the magnetic valve is caused to open, permitting water to flow to the spray heads. When sufficient moisture has been added to the air, the humidistat circuit opens, thus closing the water valve and shutting off the spray. Generally, in a forced air system, these sprays are permitted to operate only at such time as the blower is operating. The result of this is that very frequently when the system is first starting up, the blower and the magnetic valve will both attempt to operate at the same time. The starting current taken by the blower motor causes a very decided momentary decrease in line voltage. If only this decreased line voltage is available for opening the water valve, the valve is quite apt to stick because generally these valves are of the so-called impact type, and with decidedly reduced line voltage the initial impact relied on to open the valve is lacking and the valve will fail to open but sets up a very annoying hum or chatter. A particular object of my invention is to provide a time delay between the starting of the motor and the opening of the valve, so that full line voltage will be restored and available for opening the valve.

Further, in such systems, it is quite common to arrange the sprays so that they will flush the air filters free from dirt. However, it has been found that if the blower is running at the same time, the air forces the dirt against the filter so tightly that the water is unable to flush it down and clear the filter. It therefore becomes desirable to operate the sprays for a short time when the blower is not running, so that the accumulated dirt can be washed away. I advantageously utilize the same time delay element to keep the water valve open for a short while after the motor stops.

In the drawing, I have shown the complete circuit for an air-conditioning system of the type just described. In this drawing, 1 is a conventional room thermostat arranged to close contacts 3 and 2 when the temperature falls and to close contacts 3 and 4 when the tem-

perature rises. 5 is a manually operated switch arranged to have contacts 6 and 7 close and contacts 8 and 9 open when the system is being used for heating, and to have contacts 6 and 7 open and contacts 8 and 9 close when the system is being used for air-circulation in the summer time. 10 is a thermal switch or furnacestat, and is generally arranged with its actuating element in the bonnet of a warm air furnace. This switch is equipped with fan control contacts 11 and 12 so arranged that below a pre-determined temperature these contacts are open and above a predetermined temperature they are closed. It is also equipped with draft control contacts 14 and 15 so arranged that above a predetermined temperature these contacts are open and below a predetermined temperature these contacts are closed. It is also equipped with an emergency contact 13 so arranged that above a predetermined temperature contacts 13 and 14 are closed.

A draft controller 16 is so arranged that when its actuating coil 17 is energized it opens the draft and closes the check, and, when de-energized, it closes the draft and opens the check. 25 A standard transformer 18 is equipped with primary winding 20 and secondary winding 19 for feeding low voltage to the control circuit. 21 is any type of suitable relay arranged when energized to close contacts 22 and 23 and open contacts 41 and 42, and when deenergized to open contacts 22 and 23 and close contacts 41 and 42. A manually operated switch 24 is so arranged that contact 25 may be connected either to contact 27 or contact 26, or left disconnected entirely. 28 is any type of commercial humidistat. 29 is an electrically operated water valve. 30 is a transformer similar to transformer 18 and is equipped with a primary coil 31 and a secondary coil 32. 33 is any commercial air blower for forcing the air through the ducts of the air-conditioning system, including the screen or humidifier 33'. 34 is an auto-transformer delivering low-voltage across terminals 35 and 36. 37 is a warp switch of conventional design, so arranged that when heating coil 38 is energized a time delay is introduced before contacts 39 and 40 close. Similarly, when coil 38 is deenergized, a time delay is introduced before contacts 39 and 40 open.

The operation of the system will now be described: When set for winter operation, switch 5 will have contacts 6 and 7 closed and contacts 8 and 9 open. When room thermostat 1 calls for heat, contacts 2 and 3 will be closed, estab-

50

55

lishing the following circuit: contact 2, wire 43, switch 5, wire 44, contact 14, contact 15, wire 45, damper control coil 17, wire 46, wire 47, transformer secondary 19, wire 48, damper control 18, wire 49, wire 50 and contact 3. The closing of this circuit energizes damper control coil 17, causing it to open the draft and close the check on the furnace. This results in accelerating the fire and increasing the heat in the bonnet of the furnace. As soon as the temperature in the bonnet of the furnace has reached the predetermined point, contacts 11 and 12 are closed, completing the following circuit: Transformer secondary 19, wire 47, wire 51, relay 21, wire 52, wire 53, contact 11, contact 12, wire 54, wire 44, switch 5, wire 43, contact 2, contact 3, wire 50, wire 49, damper control 16, wire 48, to transformer secondary 19. The closing of this circuit energizes relay 21, which results in closing relay contacts 22 and 23 and opening relay contacts 41 and 42.

The closing of relay contacts 22 and 23 starts the blower motor 33 through the following circuit: From the line through wire 55, wire 56, contact 22, contact 23, wire 57, wire 58, blower motor 33, wire 59, wire 60 and back into the line. Blower 33 immediately starts, and, in addition, the circuit to auto-transformer 34 is energized through the following circuit: wire 55, wire 56, contact 22, contact 23, wire 57, wire 62, auto-transformer 34, wire 61, wire 60. Energizing auto-transformer 34 causes low voltage current to flow in the secondary circuit, which consists of wire 63, coil 38, and wire 64. The heating of coil 38 causes the warping member 39 to move towards contact 40. After a suitable lapse of time it establishes contact, which results in closing the following circuit: From the line through wire 60, wire 61, wire 63, contact 39, contact 40, wire 65, transformer primary 31, wire 66, wire 55 to the line. This energizes transformer 30, and if humidistat 28 is calling for more moisture in the air, and switch 24 set so that contacts 25 and 26 are closed, water valve 29 is opened through the following circuit: transformer secondary 32, wire 68, contact 25, contact 26, wire 69, humidistat 28, wire 70, contact 27, wire 71, water valve 29, wire 67, to transformer secondary 32.

In the cycle of operation just described blower motor 33 always starts a predetermined length of time before water valve 29 opens. This permits blower motor 33 to attain full speed and allows full line voltage conditions to be restored in the circuit before water valve 29 opens. This is necessary because if water valve 29 is of the magnetic impact type, it is quite likely to fail to open under reduced voltage conditions. The spraying or flushing down of the filter 33' during periods when blower motor 33 is not operating is accomplished just at the end of each operating period. The end of the operating period is initiated by the opening of contacts 2 and 3 in room thermostat 1. This immediately results in deenergizing relay 21 and the opening of relay contacts 22 and 23 and the closing of relay contacts 41 and 42. Opening contacts 22 and 23 immediately stops the operation of blower 33, but transformer 30 is still energized, due to the delay of warp switch 37 opening its contacts 38 and 40.

Since transformer 30 is energized, water valve 29 remains open the instant relay 21 is deenergized because of the establishment of the following circuit: water valve 29, transformer second-

ary 32, wire 68, wire 72, contact 42, contact 41, wire 73, wire 74, to water valve 29. Accordingly, the water valve 29 will remain open and the sprays will operate to flush the filter 33' during the time that warp switch 37 is cooling and until it has cooled sufficiently to open contacts 39 and 40. This flushing action occurs at the end of each operating period, regardless of the position of switch 24 and regardless of whether humidistat 28 is in the open or closed position.

For air circulation in the summertime, switch 5 is thrown to close contacts 8 and 9 and open contacts 6 and 7. Then, whenever the temperature of the room rises sufficiently high to cause contacts 3 and 4 of room thermostat 1 to close, the blower operates through the following circuit: contact 4, wire 74, contact 9, contact 8, wire 75, wire 52, relay 21, wire 51, wire 47, transformer secondary 19, wire 48, damper control 16, wire 49, wire 50, and to contact 3. Energizing relay 21 starts the blower, as previously described, and at the end of each period of blower operation, the air-filters will be flushed down, the same as in wintertime operation.

It is not essential that the invention broadly be associated with the temperature control of a heating system. A simple circuit arrangement may be had including only the blower motor 33, water valve 29, and humidistat 28, with a control element similar to the room thermostat 1. Essentially, the time delay element 37, whatever form it may take, and I contemplate the use of any type of construction for it, operates advantageously to initiate operation of water valve 29 after blower motor 33 has started and the line voltage is again normal. Time delay element 37 further operates advantageously to cause continued operation of water valve 29 after the blower motor 33 has stopped, in order to assure washing of filter 33'.

Without further elaboration, the foregoing will so fully explain the gist of my invention that others may, by applying current knowledge, readily adapt the same for use under varying conditions of service, without eliminating certain features, which may properly be said to constitute the essential items of novelty involved, which items are intended to be defined and secured to me by the following claims.

I claim:

1. In an air conditioning system, the combination of a motor driven air blower, a humidifier, an electrically operated valve controlling the flow of moisture to said humidifier, a control circuit for said parts, and a time-delay element in said control circuit for delaying the opening of said valve until after said motor driven air blower is in operation.

2. In an air conditioning system, the combination of a motor-driven air blower, a humidifier, an electrically operated valve controlling the flow of moisture to said humidifier, a control circuit for said parts, and a time-delay element in said control circuit for delaying the closing of said valve until after said motor driven air blower is stopped.

3. In an air conditioning system, the combination of an air blower, a humidifier and a source of liquid supply therefor, an electrically operated valve for controlling said liquid supply, a control circuit including a source of electric potential, a regulator for said control circuit rendering said air blower operative, and means for delaying the operation of said electrically operated valve until said air blower has been

rendered operative and the line potential has been restored.

4. In an air conditioning system, the combination of an air blower, a humidifier and a source of liquid supply therefor, a valve for controlling said liquid supply, a regulator for rendering said air blower operative, a humidistat, and connections between said humidistat, said valve and said regulator for opening said valve to supply liquid to said humidifier when the operation of said air blower is stopped by said regulator irrespective of the condition of said humidistat.

5. In an air conditioning system, the combination of an air blower, a humidifier and a source of liquid supply therefor, a valve for controlling said liquid supply, a control circuit for said air blower, an auxiliary control circuit having means therein for operating said valve, and connections between said control circuit and said auxiliary control circuit for closing said auxiliary circuit upon the opening of said control circuit.

6. In an air conditioning system, the combination of an air blower, a humidifier and a source of liquid supply therefor, a valve for controlling said liquid supply, a control circuit for said air blower, an auxiliary control circuit having means therein for operating said valve, a humidistat for controlling said auxiliary circuit, and connections between said control circuit and said auxiliary circuit for closing said auxiliary circuit, irrespective of the condition of said humidistat, upon the opening of said control circuit.

7. In an air conditioning system, the combination of an air blower, a humidifier and a source of liquid supply therefor, a valve for controlling said liquid supply, a control circuit for said air blower, an auxiliary control circuit having means therein for operating said valve, a humidistat for controlling said auxiliary circuit, and an automatic circuit-making-and-breaking device between said control circuit and said auxiliary circuit for closing said auxiliary circuit when said control circuit is open whereby to operate said valve means irrespective of the condition of said humidistat.

8. In an air conditioning system, the combination of an air blower, a humidifier and a source of liquid supply therefor, a valve for controlling said liquid supply, a control circuit for said air blower, an auxiliary control circuit having means therein for operating said valve, and an automatic circuit making-and-breaking-device between said control circuit and said auxiliary circuit for closing said auxiliary circuit when said control circuit is open whereby to operate said valve means.

9. In an air conditioning system, the combination of an air blower, a humidifier and a source of liquid supply therefor, a valve for controlling said liquid supply, a control circuit for said air blower, an auxiliary control circuit having means therein for operating said valve, an automatic circuit making-and-breaking device between said control circuit and said auxiliary circuit for closing said auxiliary circuit when said control circuit is open, and a time delay circuit making-

and-breaking element between said control circuit and said auxiliary circuit for continuing the flow of current through said auxiliary circuit for a predetermined period of time after said control circuit is opened.

10. In an air conditioning system, the combination of an air blower, a humidifier and a source of liquid supply therefor, a valve for controlling said liquid supply, a control circuit for said air blower, an auxiliary control circuit having means therein for operating said valve, and a time-delay circuit-making-and-breaking element between said control circuit and said auxiliary circuit for effecting a time-delay in the operation of said auxiliary circuit after the 15 operation of said control circuit.

11. In an air conditioning system, the combination of an air blower, a humidifier and a source of liquid supply therefor, a valve for controlling said liquid supply, a control circuit for said air blower, an auxiliary control circuit having means therein for operating said valve, a time-delay circuit-making-and-breaking element between said control circuit and said auxiliary circuit for effecting a time-delay in the 20 operation of said auxiliary circuit after the operation of said control circuit, and means for closing said auxiliary circuit when the operation of said air blower is stopped.

12. In an air conditioning system, the combination of an air blower, a humidifier and a source of liquid supply therefor, a valve for controlling said liquid supply, a control circuit for said air blower, an auxiliary control circuit having means therein for operating said valve, a time-delay circuit-making-and-breaking element between said control circuit and said auxiliary circuit for effecting a time-delay in the 25 operation of said auxiliary circuit after the operation of said control circuit, and a relay for closing said auxiliary circuit when said control circuit is opened.

13. In an air conditioning system, the combination of an air blower, a humidifier and a source of liquid supply therefor, a valve for controlling said liquid supply, a control circuit for said air blower, an auxiliary control circuit having means therein for operating said valve, and a thermally operated element controlled by the heat effects of the current flow through 35 said control circuit for controlling the flow of current through said auxiliary circuit, said thermally operated element effecting a time-delay 40 with respect to the current flow in said control circuit, in controlling the flow of current in said auxiliary circuit.

14. In an air conditioning system, the combination of an air blower, a humidifier, and a source of liquid supply therefor, a control circuit for said air blower, a valve for controlling said liquid supply, an auxiliary control circuit for said valve, and a thermally operable element controlled by the current flowing through said blower control circuit for controlling the flow of current through said auxiliary control circuit.

JOHN S. BAKER. 65
